REEL FOR PICTURE MACHINES

Joseph K. E. Sunell, Hempstead, N. Y., assignor of forty-nine per cent to Dominick Santora, Hempstead, N. Y., and twenty-five and one-half per cent to Emil Niklaus, Nilsson, Franklin Square, N. Y.

Application June 1, 1939, Serial No. 276,879

6 Claims. (Cl. 88—18.7)

This invention relates to projection machines and has special reference to the winding of a photographic film in such a machine.

More particularly the invention relates to an improvement on my prior application No. 212,343, filed June 7, 1938, for a machine of this class.

The most important object of the present invention is to provide a generally improved form of such a machine.

With the above and other objects in view the invention consists in general of certain novel details of construction and combinations of parts hereinafter fully described, illustrated in the accompanying drawings, and specifically set forth in the claims.

In the accompanying drawings, like characters of reference indicate like parts in the several views, and:

Figure 1 is a front elevation of the improved winding device with the face of the cover removed.

Figure 2 is a detail view showing the construction illustrated in Figure 1 of the moving parts from the rear thereof.

Figure 3 is a detail section partly in elevation and partly in section on the line 3—3 of Figure 1.

Figure 4 is a fragmentary detail on an enlarged scale showing the manner in which the supporting rollers of the film are carried.

Figure 5 is a detail view showing, in section, the manner of connecting the clip of the carrier ring.

Figure 6 is a further detail view of such ring to a greatly enlarged scale showing the manner of holding the same in position in the main part of the device.

In the device as herein disclosed there is provided a casing 10 which may or may not, as may be desired, have a cover hinge thereon, said cover being of glass or having a glass panel. Secured in this casing by screws 11 is a bracket 12 having a journal opening at the center thereof. This bracket 12 supports a shaft 14 as best shown in Figure 3. On the outer end of this shaft there is provided a plate 15 having a hub 16 which is keyed or otherwise secured to the shaft 14 so that the shaft and hub rotate together. This plate 15 is provided with a series of arcuate slots 17. Also fixed to the bracket 12 is a plate 17' carrying a series of radial channel members 18 wherein are slideably held the heads 19 of shafts 20 each of which carries a rotary film supporting roller 21 having flanges 22 at its ends. The bracket 12 has a series of radial arms each of which is provided with an opening 23 where-

through extends the stem 24 of a yoke member 25 carrying a roller 26 having flanged ends 27. There are at least three of these rollers as can be seen from Figure 1 and these rollers support a ring 28 having a gear 29 on the outer face thereof. This gear 29 is engaged by a pinion 30 which may be turned by any suitable means, so that when the pinion is rotated the gear will rotate. The shafts of the rollers 21 pass through the slots 17 and also carry the heads 19. Now it is to be noted that the plate 17' is fixed while the plate 15 rotates. This plate rotates with the hub so that when this rotation takes place the arcuate slot 17 acts as cams to move the rollers 21 in and out.

The casing 10 is provided with an inlet where the film enters and adjacent this inlet is a guide roller 31 which leads the film to a second guide roller 32 and from there to a guide roller 33 carried by the fixed plate 17' and having its stem passing through a slot 34 so that rotation of the plate 15 is permitted without interfering with the guide roller 33. Similarly there is a second guide roller 35 carried by the plate 17' and having a stem extending through a slot 36. It will be seen from Figure 1 that the film enters and passes over the guide roller 31, over the roller 32, around the roller 33, then to the roller 35 and thence to one of the rollers 21.

Fixed on the hub 16 is a grooved segment 37 at one end of which is secured the one end of a spring 38 which has its other end secured to a bracket 39 fixed on the member 12. The object of this spring is to constantly urge the rotation of the member 28 in the direction of the arrow on Figure 2. Also there is fixed on the hub 16 a ratchet wheel 40 normally engaged by a pawl 41 which may be released from the ratchet at will. In order to release the pawl 41 from the ratchet there is provided a plunger 42 which extends through a bracket 43 connected to the upper part of the member 12 and on the upper end of this bracket 43 is a push button 44 which is held in elevated position by a spring 45. The arrangement here is such that when the push button is pushed downwardly then the pawl 41 is released from the ratchet 40 and the spring 38 is allowed to act on the segment 37 so as to turn the member 15 in the direction of the arrow shown in Figure 2.

Between the rollers 21 and the member 28 there is normally interposed a split ring 46 hinged as at 47 to open and close and provided with a snap lock indicated in general at 48. This snap lock consists of a bevelled end 49 on one side of the

lock and a spring 50 fixed to the other side to engage with its notched or bevelled end 51 on the latch 49. Also there is provided a releasing member 52 which, by pushing in the direction of the member 49 will release the latch 51.

Furthermore at suitable places around the device the ring 28 and the split ring 46 are provided with latching means indicated in general at 53, these latching means consisting of a spring latch 54 which normally engages a shoulder 55 10 formed in a groove 56 in the member 28, the spring latch 53 being provided with a button or head 57 whereby the shoulder portion 54 may be released from the shoulder 55.

Now under these circumstances when the film leads into the device it passes around within side of the member 46 and, by reason of the arcuate slots 17 forces the member 15 to revolve since the rollers are forced directly inward in a radial direction on account of the slots 18. Therefore 15 the member 15 may, as one may say, wind up and cause the spring 38 to expand by reason of the fact that the segment 37 rotates in the opposite direction of that shown in Figure 2. Thus the ratchet 40 rotates and is held in its rotated position by the pawl 41 until it is desired to release the apparatus. After this the buttons 57 20 may be drawn to position to release the inner ring 46 whereupon the inner ring with the film may be removed from the remainder of the device.

The initial movement is to thread ribbon in by hand until it is gripped between one of the rollers 22 and the ring 46. Then by slightly rotating ring 46 the ribbon is fed to be gripped by several of said rollers and the continuation of rotation of the ring 46 winds the ribbon against the inner side of this ring without any attachment thereto. The spring 38 rotates the shaft 14 when the pawl 41 is released from the ratchet 40. Now, the purpose of this is to urge the rollers 22 outwardly against the ring 46. The ring rotates continuously during winding, the plate only rotates 30 part way.

There has thus been provided a simple and efficient device of the kind described and for the purpose specified.

It is obvious that minor changes may be made in the form and construction of the invention without departing therefrom. It is not therefore desired to confine the invention to the exact form herein shown and described but it is desired to include all forms which properly come 40 within the scope claimed.

Having thus described the invention what is claimed as new is:

1. In a device of the kind described, a fixed plate having radial guides thereon, a rotary plate having cam grooves cooperating with said guides, means supporting said fixed plate, a shaft extending centrally of the fixed plate and having the remaining plate rotatable therewith, film supporting rollers having guide portions in the fixed and radial guides, an outer ring rotatably supported concentrically of said shaft, an inner ring supported between said rollers and outer ring, guide means directing a film strip between said rollers and inner ring, and means for releasably securing the inner ring within the outer ring.

2. In a device of the kind described, a fixed plate having radial guides thereon, a rotary plate having cam grooves cooperating with said guides, means supporting said fixed plate, a shaft extending centrally of the fixed plate and having

the remaining plate rotatable therewith, film supporting rollers having guide portions in the fixed and radial guides, an outer ring rotatably supported concentrically of said shaft, an inner ring supported between said rollers and outer ring, guide means directing a film strip between said rollers and inner ring, and means for releasably securing the inner ring within the outer ring, said inner ring consisting of a plurality of hinged portions having locking means.

3. In a device of the kind described, a fixed plate having radial guides thereon, a rotary plate having cam grooves cooperating with said guides, means supporting said fixed plate, a shaft extending centrally of the fixed plate and having the remaining plate rotatable therewith, film supporting rollers having guide portions in the fixed and radial guides, an outer ring rotatably supported concentrically of said shaft, an inner ring supported between said rollers and outer ring, guide means directing a film strip between said rollers and inner ring, and means for releasably securing the inner ring within the outer ring, the ring provided with the cam grooves having a hub, a grooved segment fixed on said hub, a coiled compression spring having one end secured to said segment and the remaining end secured to a fixed member whereby to rotate the segment and the cam grooved plate 30 in one direction.

4. In a device of the kind described, a fixed plate having radial guides thereon, a rotary plate having cam grooves traversing said guides, means supporting said fixed plate, a shaft extending centrally of the fixed plate and having the remaining plate rotatable therewith, film supporting rollers having guide portions in the fixed and radial guides, an outer ring rotatably supported concentrically of said shaft, an inner ring supported between said rollers and outer ring, guide means directing a film strip between said rollers and inner ring, and means for releasably securing the inner ring within the outer ring, said inner ring consisting of a plurality of hinged portions and means for holding said inner ring in circular position releasably, the ring provided with the cam grooves having a hub, a grooved segment fixed on said hub, a coiled compression spring having one end secured to said segment and the remaining end secured to a fixed member whereby to rotate the segment and the cam grooved plate in one direction.

5. In a device of the kind described, a fixed plate having radial guides thereon, a rotary plate having cam grooves, means supporting said fixed plate, a shaft extending centrally of the fixed plate and having the remaining plate rotatable therewith, film supporting rollers having guide portions in the fixed and radial guides, an outer ring rotatably supported concentrically of said shaft, an inner ring supported between said rollers and outer ring, guide means directing a film strip between said rollers and inner ring, a spring to draw the cam-grooved plate in one direction, and ratchet means holding said spring under tension.

6. In a device of the kind described, a fixed plate having radial guides thereon, a rotary plate having cam grooves, means supporting said fixed plate, a shaft extending centrally of the fixed plate and having the remaining plate rotatable therewith, film supporting rollers having guide portions in the fixed and radial guides, an outer ring rotatably supported concentrically of said shaft, an inner ring supported between said

rollers and outer ring, guide means directing a film strip between said rollers and inner ring, and means for releasably securing the inner ring within the outer ring, said inner ring consisting of a plurality of hinged portions and means for holding said inner ring in circular position releasably, the ring provided with the cam grooves having a hub, a grooved segment

fixed on said hub, a coiled compression spring having one end secured to said segment and the remaining end secured to a fixed member whereby to rotate the segment and the cam grooved plate in one direction, and ratchet means holding said spring under tension.

JOSEPH K. E. SUNELL.
